UNITED STATES PATENT OFFICE

2,567,780

HURRICANE LAMP ADAPTER FOR
CANDLESTICKSWilliam P. Oppelt, Meriden, Conn., assignor to
The International Silver Company, Meriden,
Conn., a corporation of Connecticut

Application October 14, 1950, Serial No. 190,159

1 Claim. (Cl. 240—13)

1 This invention relates to an adapter for use with a candlestick to convert the same to a hurricane lamp type of structure and to a novel construction for resiliently gripping the glass chimney of a lamp of this type.

An object of the invention is to provide a device which will hold a candle and firmly support a glass chimney for the candle on a candlestick.

Another object is to make provision in a device of this type for the carriage of a glass chimney securely and tightly positioned against tipping or otherwise being displaced in a holder.

Other objects and advantages of the invention will become apparent in the following specification and accompanying drawings, in which:

Fig. 1 is a side elevation of the adapter in position on a candlestick;

Fig. 2 is a view on line 2—2 of Fig. 1; and

Fig. 3 is a view on line 3—3 of Fig. 1.

The lamp adapter may be made of any resilient metallic material such as spring steel. At the base of the adapter a cylindrical socket member 2 is provided for insertion in a candle holder opening 3 of a candlestick 4. In the form shown the socket 2 has exterior threads 5 which mate with threads 6 of the candlestick opening 3 so as to secure the adapter firmly in place. The threads 5 may also be impressed in the inner wall of socket 2 as shown and provide a secure grip for a candle 7 inserted therein.

Formed integrally with the wall of socket 2 and flared outwardly and upwardly from the upper edge thereof is a cupped annular flange 8 forming a base for the holder portion to support a glass hurricane lamp chimney 10.

The chimney holder portion is concentric with socket 2 and comprises an integral vertically and upwardly extending cylindrical portion above flange 8. The holder portion engages and releasably grips the cylindrical base portion 9 of chimney 10. In the lower section of said holder portion adjacent flange 8, a series of annularly disposed venting openings 11 is provided to admit air under the lower edge 9' of the base of chimney 10 for an air supply to the candle when lighted.

The upper portion of the chimney holder is formed with two spaced imperforate ring sections, a lower section 12, and an upper section 13. Disposed between the ring sections 12 and 13 and integrally joining the same is a series of resilient ribs or slats 14. The slats 14 are all uniformly bowed or arched inwardly from the plane of the ring sections as by deforming the spring metal of the holder. The slats form an

intermediate spring belt or girdle section between the rings and are provided at their mid portions with enlargements 15 for a greater bearing surface against the glass. When the cylindrical base 9 of a chimney 10 is inserted in the holder the enlarged cylindrical mid section of the slats encircle the outer wall of the chimney base and the slats are forced to spread outwardly. The slats being of resilient spring metal hold the

10 chimney base securely and firmly gripped against tipping or shifting. When the chimney is removed for cleaning or otherwise the inwardly urged slats return to their normal inwardly bowed condition. The upper ring 13 is provided at the top edge thereof with an outwardly rolled beaded lip 16. Lip 16 forms a seat against which the flared or bulged portion 17 of the lamp chimney rests. Thus, shown, the lower edge 9' of the chimney is positioned adjacent the vents

20 11.

It is of particular importance in the use of such glass chimneys that the chimney be held steadily and firmly in position, as a slight displacement or inclination in its holder may cause 25 the heat from a candle flame to crack the glass. In addition the usual chimneys are made of blown glass rather than cast glass. Considerable variations in standard sizes result from the method of manufacture. Thus a holder must be adapted 30 to accommodate and effectively support chimneys having many different variations introduced in the standard sizes. The adapter of the construction shown herein is designed to accomplish this object.

35 With these considerations in mind, the adapter has been constructed to give effective service under long-continued use. It will be noted the openings between the ribs or slats are generally diamond-shaped, with the enlargements 15

40 formed at the mid points, so that the extremities as well as the central portions of the slats 14 are provided with added rigidity and strength. Accidental displacement of an individual slat 14 with respect to the others is impossible with

45 the integral connection at top and bottom of the rings 12 and 13. Thus the engirdling belt section for resiliently gripping the base portion of the chimney is afforded a substantial degree of structural support for securely holding the glass in place.

50 While the invention has been disclosed with particular relationship to its utility for use with candlesticks, it will be recognized that the unitary construction of the rings 12 and 13 in conjunction with the slats or vents 14 is equally useful for

analogous applications. Thus, as one example, the arrangement may be utilized to support the glass chimney in electric table or mantle lamps which simulate the old fashioned oil table lamps.

What I claim is:

An adapter for candlesticks providing a socket to hold a candle and a holder for supporting a hurricane lamp chimney having a cylindrical base portion and a chimney portion with an outwardly flared bulge joined to said base, said adapter comprising a cylindrical socket for the base of the adapter and having threads in the wall thereof for engagement in a threaded candlestick opening and for gripping the base of a candle inserted in said socket, an annular cupped flange outwardly and upwardly flared from the top edge of said socket to provide the base portion of a chimney holder, a cylindrical chimney holder portion extending upwardly from the flange and having a diameter of greater dimension than said socket, said holder portion being disposed concentrically of said socket and having in the lower section thereof adjacent the flange a series of vents to admit air to the base of a chimney in the holder, an imperforate lower ring section above said vents and an imperforate upper ring section spaced upwardly therefrom, a resilient girdle section joining said rings, said ring sections being in substantially the same

5 plane, with said girdle section having inwardly arched slatted ribs deformed from and connecting said rings, the central mid portions of said ribs being enlarged and forming a cylindrical girdle inwardly of the plane of the rings for providing resilient gripping pressure against the base of a lamp chimney inserted therein, the top peripheral edge of said upper ring section being adapted to provide a seat for the flared portion of said chimney with the lower edge of the base of said chimney resting adjacent said air vents of the adapter.
